INVENTOR.

JOHN BINA

Ralph W. Brown,
ATTORNEY

ATTORNEY.

UNITED STATES PATENT OFFICE.

JOHN BINA, OF MILWAUKEE, WISCONSIN.

ROOM INDICATOR.

Application filed August 5, 1921. Serial No. 489,969.

To all whom it may concern:

Be it known that I, JOHN BINA, a citizen of the United States, residing at Milwaukee, in the county of Milwaukee and State of Wisconsin, have invented a certain new and useful Improvement in Room Indicators, of which the following is a full, clear, concise, and exact description, reference being had to the accompanying drawings, forming a part of this specification.

This invention relates to lock actuated room indicators.

The occupants of hotel rooms, state rooms, etc., are not infrequently annoyed by the untimely entry, or attempted entry, of the servants or attendants in the course of their usual duties. Actual entry may ordinarily be prevented by the use of the inside lock with which these rooms are usually provided and which cannot be operated except from the inside; but attempted entries can not be avoided unless some means be provided by which the servant or attendant may know of the locked or occupied condition of the room.

Various lock actuated devices have heretofore been designed for automatically indicating the locked or unlocked condition of a door or the occupied or unoccupied condition of a room. As heretofore constructed, however, these devices can ordinarily be used only with a particular form of lock and their installation usually requires some modification of the lock mechanism.

One object of the present invention is the provision of an improved type of lock actuated indicator for the purpose above outlined, capable of universal application and use with locks of various forms, without requiring any modification of the lock or lock mechanism.

Another object is the provision of an improved type of indicator, which will not only automatically respond to the positions of the lock but which may be manually set to indicate a given condition of the room. This feature is particularly useful in hotels and the like, where it is desirable to indicate, for instance, when the room has been cleaned up for the day and is ready for occupancy.

Other objects and advantages will herein-after appear.

One embodiment of the invention is illustrated in the accompanying drawings, in which:

Figure 1 is a fragmentary view in front elevation of a conventional form of door and door casing equipped with a lock actuated indicator constructed in accordance with the present invention.

Figure 2 is a horizontal sectional view on a somewhat larger scale of the parts shown in Figure 1.

Figure 3 is a sectional view taken substantially on the line 3-3 of Figure 2.

Figure 4 is a sectional view taken substantially on the line 4-4 of Figures 2 and 6.

Figures 5, 6 and 7 are front views of the indicator proper, with the face plate partially broken away, and respectively illustrating the three different positions of the indicator.

For convenience of illustration and description, the invention is shown and will be described as embodied in an indicator mounted upon a door casing, although it may be advantageously embodied in an indicator designed for mounting upon the door.

A door 10 of conventional form is shown in Figures 1 and 2 of the drawings. This door is mounted in the usual manner, within the door casing 11 of standard construction. A lock mechanism of any appropriate type is carried by the door. The lock mechanism shown is provided with the usual door knobs 12 and with two lock bolts. One of the lock bolts shown at 13 is operable by a key 14 insertable through a key hole 15 on the inner side of the door, while the other lock bolt (not shown) may be operated from either side of the door through one of the key holes 16. When in locking position, the active end of the lock bolt 13 projects into a socket 17 within the door casing, in the usual manner, to secure the door against opening. The parts thus far described are of a well known construction, so that a further or more detailed description thereof is deemed unnecessary.

The indicator selected for illustration includes a base plate 18 and a dished cover or face plate 19 cooperating therewith to form a casing or chamber 20. These plates are secured together by any appropriate means, such, for instance, as screws 21 passing through suitable registered openings therein and anchored in the face of the door casing 11. The face plate 19 is provided with a sight opening 19'. A signal plate or tar-

get 22 is mounted within a suitable guideway formed within the casing 20 and extending beneath the sight opening. The guideway is formed preferably by slitting 5 and bending up portions of the base plate 18 to form a pair of upstanding guide flanges 23 between which the target 22 is positioned for vertical sliding movement. The target is arranged to assume either of three 10 positions with respect to the sight opening. In one position (Fig. 5), the upper portion only of the target is visible beneath the sight opening; in a second position (Fig. 6), the lower portion only of the target is visible; 15 and in the third position (Fig. 7), the target is completely withdrawn from beneath the sight opening, so that a portion of the base plate 18 is visible therethrough. The upper and lower portions of the target, as well as 20 the portion of the base plate 18 beneath the opening, preferably bear characteristic colors or symbols corresponding to different conditions of the lock or room. For instance, in the indicator shown the lower portion 25 of the target carries the symbol "In" to indicate that the room is occupied and the occupant does not want to be disturbed; the upper portion carries the symbol "Out" to indicate that the room is unoccupied or that 30 the servant or attendant may enter to take care of the room; and the base plate 18 carries the symbol "Inspected" to indicate that the room has been taken care of by the servant 35 or attendant.

Lock actuated mechanism is employed for effecting an automatic adjustment of the indicator to either of the two positions first named, while mechanism adapted to be actuated by the servant or attendant is preferably provided for effecting an adjustment to 40 the third position. These mechanisms may assume various forms. The lock actuated mechanism is preferably arranged, however, to be actuated by the active end of the lock bolt 13, that is, the end of the bolt that enters the socket 17, so that the indicator may 45 be associated with and actuated by the lock without requiring a modification of the lock mechanism. When the indicator is applied 50 to the door casing, a lock actuated mechanism, such as will now be described, may be advantageously employed.

This mechanism includes a plunger 24, arranged preferably in substantial alignment 55 with the lock bolt 13. This plunger is preferably reciprocally mounted in a tubular member 25 seated within a suitable bore formed within the door casing and communicating with the socket 17. A compression spring 26 tends at all times to project the plunger into the socket 17 toward the lock bolt 13. For purposes of adjustment, one 60 end of the plunger 24 is provided with a contact screw 27 screwed into the end of the plunger and adapted to bear against the end 65

face of the lock bolt, when the bolt is advanced to locking position. The plunger is preferably reduced, as at 28, to form a shoulder 29, the reduced portion being provided with rack teeth 30 adapted to mesh with a suitable pinion 31 carried by a rock shaft 32.

The indicator is actuated by the rock shaft 32. The doors of hotel rooms are ordinarily mounted to open inwardly and the indicator must be visible from the outside, so that it usually becomes necessary that the rock shaft 32 extend substantially through the door casing from front to rear. For this reason, a longitudinally adjustable shaft is 75 preferably employed so that it may be accommodated to door casings of various widths. The rock shaft shown is therefore made up of two short lengths of shafting having telescopic interengagement. One 80 length of shafting 33 carries at one end the pinion 31 and is squared at the other end for a sliding fit within the squared tubular shafting 34.

The free end of the tubular shafting 34 90 fits over and embraces a squared turnbutton 35 secured to one end of a stub shaft 36 rotatably mounted within the base plate 18 of the indicator. The other end of this stub shaft 36 carries a cam or lever 37 for actuating the target 22. The stub shaft 36 and lever 37 are preferably arranged within the bottom portion of the casing 20 beneath the lower edge of the target, so that when the lever 37 is swung to an upright position the 100 target is raised to its uppermost position with the lower portion thereof exposed through the sight opening. When the lever 37 is swung downwardly the target falls by gravity to a lower position.

Any appropriate manually operable means, such as a detent lever 38, may be provided for limiting the downward movement of the target. This lever 38 is pivotally mounted, as at 39, preferably upon the base plate 18, in position beneath the lower edge of the target. This lever is of such length that when in its normal upright position the downward movement of the target is limited and the target held thereby in such 110 position that the upper portion thereof is exposed through the sight opening. This lever, however, when swung to its lower position, permits the target to fall to its lowermost position, where it is entirely below the 120 sight opening and a portion of the base plate is exposed through the opening. The two levers 37 and 38 are preferably arranged so as to swing toward each other and so that the lever 38, when in its lower position, is within the path of movement of lever 37 (see Fig. 7). Thus, when the lever 37 is 125 swung upwardly the lever 38 is forced thereby into its upright position, shown in Figures 5 and 6. To return it to its lower 130

position, any appropriate means, such as a knob 40, is provided, connected with the pivot pin 39 and projecting from the face plate 19, where it may be readily grasped and manipulated by the servant or attendant.

In operation, lever 38 is normally in the upright position shown in Figures 5 and 6. When the lock bolt 13 is thrown to locking position, with the active end thereof projecting into the socket 17, the plunger 24 is forced to the right against the pressure of the spring 26, the rock shaft 32 is rotated, and the lever 37 swung to its upright position as shown in Figure 6. The target is thus forced upwardly by the lever 37 so that the indicator shows "In". The servant may thus tell, at a glance, that the room is occupied and that the occupant does not wish to be disturbed.

When the occupant leaves the room, however, he turns the key and withdraws the lock bolt 13 to release the lock. As soon as released, the plunger 24 is automatically shifted to the left (Fig. 2) under the action of the spring 26. This movement of the plunger is limited by the contact of the shoulder 29 with the pinion 31. This movement of the plunger is sufficient, however, to swing the lever 37 to its lower position of Figure 5 by rotation of the pinion 31, rock shaft 32 and turn button 35. The target 24 is thus permitted to fall by gravity until it strikes the upstanding lever 38, in which position the indicator shows "Out". The servant may thus tell, at a glance, that the room is either unoccupied or that the occupant is willing to have the servant enter for the purpose of taking care of the room. Should the occupant again lock the door by throwing the lock bolt 13 to locking position, the indicator would again be thrown to the position showing "In", in the manner above described.

When the servant has cleaned up the room for the day, he turns the knob 40 to the right (Fig. 1), thus swinging the lever 38 to its lower position of Figure 7. This permits the target 22 to fall by gravity to its lowermost position, where it disappears below the sight opening and the indicator shows "Inspected". The room is then again ready for occupancy. When the occupant has entered and does not want to be disturbed he locks the inner lock by turning the key 14 and thus throwing the bolt 13 to locking position. The lever 37 is thus automatically swung upwardly in the manner above described, forcing the lever 38 upwardly to its normal upright position and raising the target to its uppermost position where the indicator shows "In". The parts are thus again restored to the position shown in Figure 6.

Various changes may be made in the em-

bodiment of the invention hereinabove specifically described, without departing from or sacrificing any of the advantages of the invention as defined in the following claims.

I claim:

1. A lock actuated indicator having a movable target, lock actuated means for effecting an adjustment of said target to either of two positions, and manually actuated means for effecting an adjustment of said target to a third position.

2. A lock actuated indicator having a movable target, lock actuated means for effecting a movement of said target in either of two directions, and manually operable means for limiting the movement of said target in one direction.

3. A lock actuated indicator having a movable target, lock actuated means for effecting a movement of said target in either of two directions, means actuated by said first named means for limiting the movement of said target in one direction, and manually operable means for adjusting said limiting means to permit a further movement of said target.

4. The combination with an indicator having a sight opening and a target movable relative to said sight opening, of means for effecting a movement of said target in either of two directions, and means automatically actuated in one direction for limiting the movement of said target and manually operable in another direction to permit an extended movement of said target.

5. An indicator having a movable target, means including a lock actuated lever for effecting movement of said target in either of two directions, and manually releasable means for limiting the movement of said target in one direction.

6. An indicator having a movable target, means including a lever for effecting movement of said target in either of two directions, and means including a second lever projectable within the path of movement of said first named lever for limiting the movement of said target in one direction.

7. The combination with a lock having a lock bolt of an indicator actuated thereby, said indicator comprising signalling means, and signal actuating means, including a lock actuated member projectable into the path of movement of the active end of said lock bolt.

8. The combination with a lock having a lock bolt of an indicator actuated thereby and having signalling means, and means including a member engageable with the active end of said lock bolt for actuating said first named means.

9. In a lock actuated indicator, the combination of a signalling means, a member for contact with the active end of a lock

bolt to move therewith, and connections between said member and said signalling means for actuating said signalling means when the lock bolt is thrown to locking position.

10. The combination of a door and door casing, a lock having a lock bolt carried by said door, an indicator, and means including a member mounted in said casing and actuated by said lock bolt for actuating said indicator.

11. The combination of a door and door casing, a lock having a lock bolt carried by said door, an indicator mounted on said

door casing, and means responsive to movement of said lock bolt for adjusting said indicator in accordance with the condition of said lock. 15

12. The combination of a door and door casing, a lock, an indicator, means including a member mounted in said casing for adjusting said indicator in accordance with the condition of said lock, and additional means for effecting a further adjustment of said indicator. 20

In witness whereof, I hereunto subscribe my name this 27th day of July, 1921.

JOHN BINA. 25
